GLIDER PICKUP APPARATUS

Harry B. Cowgill, Jr., Rockville Centre, N. Y.

Application December 6, 1943, Serial No. 513,027

10 Claims. (Cl. 244—63)

1

This invention relates to apparatus useful as a means to facilitate picking up of gliders by a powered towing craft such as airplanes or dirigibles in flight.

The chief aim of my invention is to make possible the automatic coupling of a tow line from a glider at rest on the ground to the moving towing craft, and at the same time to bring the glider gradually up to speed before being actually released for direct draft through the medium of the tow line by such towing craft.

Another object of my invention is to accomplish the foregoing without subsequent encumbrance of the towing craft or glider with auxiliaries other than the tow line itself.

The above desiderata are realized in practice as hereinafter more fully disclosed through provision of a pick-up apparatus which includes a reeling unit having two freely-rotative tapered intergeared drums. To the periphery of the small end of one of these drums is secured a cable whereof the free end is self-releasably connected to a glider at rest at a distance rearward of the reeling unit as considered with respect to the direction of approach of the towing craft to which the glider is to be coupled with said cable slackened. On the other reel is wound a cable which is doubled upon itself and which has one of its ends only secured to the periphery of the drum at the small end of the latter. Positioned ahead of the reeling unit is a means for releasably supporting in horizontally open positions at an elevation, the free terminal loop of the doubled cable and a loop at the free end of the slackened tow line extending from the glider so that said loops can be engaged by a pendent hook projection on the passing towing craft. Under the pull of the towing craft the doubled cable is unwound from its drum, while, through the intergearing, the other drum is incidentally rotated to progressively wind up the other cable, with attendant impartation of accelerating movement to the glider until it has acquired the speed of said towing craft. The first mentioned cable is automatically detached from the glider when said cable is substantially completely wound on its drum and as said glider passes over the reeling unit. This occurs concurrently with complete unwinding of the second cable from its drum with attendant automatic release thereof from the projection on the towing craft at a time when the slack of the tow line has been substantially taken up for pull of the glider thereafter directly by said towing craft.

2

Other objects and attendant advantages will appear from the following description of the attached drawings, wherein

Fig. 1 is a view in side elevation showing my improved pick-up apparatus at the time of initial engagement of the loops of the tow line and the doubled cable by the pendent projection of the flying towing craft.

Fig. 2 is a diagrammatic plan view of the reeling unit corresponding to Fig. 1.

Fig. 3 is a view looking as indicated by the angled arrows III—III in Fig. 1 showing the means for supporting the loops respectively of the tow line and the doubled cable.

15 Fig. 4 is a view like Fig. 1 showing conditions at the end of the take-up operation with the cables detached respectively from the glider and the towing craft and with the glider directly connected to said towing craft.

20 Fig. 5 is a plan view of the reeling unit corresponding to Fig. 4.

Fig. 6 is a view showing the reeling unit in top plan on a larger scale.

25 Fig. 7 is a longitudinal sectional view of the reeling unit taken as indicated by the angled arrows VII—VII in Fig. 6.

Fig. 8 is a cross sectional view of the reeling unit taken as indicated by the angled arrows 30 VIII—VIII in Figs. 6 and 7.

Fig. 9 is a fragmentary sectional view of the reeling unit taken as indicated by the angled arrows IX—IX in Figs. 6 and 7.

Fig. 10 is a fragmentary view in longitudinal section showing the profile of one of the reel drums.

Fig. 11 is a view like Fig. 10 of the other drum of the reeling unit; and

40 Fig. 12 is a fragmentary sectional view taken as indicated by the angled arrows XII—XII in Fig. 11.

In these illustrations the reel of my improved glider pick-up apparatus is generally designated by the numeral 15. As shown, its two drums 16 and 17 are disposed alongside each other with their shafts 18 and 19 journaled in the side uprights 20 of a frame 21 anchored on the surface of a flat runway 22, the diameter of the small end of the drum 17 being in this instance equal to the diameter of the large end of drum 16. The drum 16, it will be noted, has a curved tapering surface with a spiral groove 23 for reception of the cable 25 whereof one end is suitably secured to 50 the small end of the drum, while its other end is

provided with an eye 26 which is adapted to be connected, with capacity for self-release in a manner later on explained, to a simple hook 27 at the front end of the glider 28. The tow line indicated at 29 is securely attached to a standard glider attachment in the nose of the glider 28 and its free end, in accordance with my invention, is formed into a relatively large loop 30 which is adapted to be placed for temporary support opened out in a horizontal plane at an elevation above ground over the tops of a pair of laterally-spaced standards 31 which are located somewhat forward of the reeling unit 15. The drum 17 is frusto-conical in configuration and has a spiral groove 32 which is considerably deeper than that of the drum 16 for capacity to receive the cable 33 which is doubled upon itself as shown in Figs. 11 and 12, and, as shown in Figs. 1 and 3, wound on said drum with attendant formation of a free loop 34 which is adapted to be placed over the standards 31 with the loop 30 of the tow line 29. In order to confine the loop 34, a tape band of fabric is wrapped at B about the doubled cable. The end of the outer layer of the cable 33 is secured to the drum 17 at the small end of the latter by clamps 35, while the end of the inner layer is simply tucked in beneath the fixed end of said outer layer as further shown in Fig. 12. From Figs. 6 and 7 it will be noted that the drums 16 and 17 are intergeared in simple, or one-to-one, ratio by chains 36 connecting sprocket wheels 37 and 38 at opposite ends of the drum shafts 18 and 19, said drums being thus arranged for simultaneous rotation at synchronous speeds.

For the purpose of insuring uniform winding of the cable 25 on the drum 16 I have provided a shifting fork 39 which is mounted on a transverse screw spindle 40 journaled in bracket extensions 41 on the side uprights 20 of the drum frame 21. By means of a sprocket chain 42 the screw spindle 40 is driven from the shaft 18 of the drum 16; and through engagement of a pendent projection 39a on the shifting fork 39 with a guide rod 43 extending crosswise between the bracket extensions 41, said fork is restrained against rotation with said spindle. As best shown in Fig. 9, the thread on the spindle 40 terminates short of the inner sides of the bracket extensions 41 so that the follower 39 may leave the thread after it has completed its traverse in either direction to preclude jamming incident to overrunning of the drum 16. The helical compression springs indicated at 45 in Fig. 9 cause the follower 39 to automatically re-engage the thread of the spindle 40 upon reversal in the rotation of the latter after winding or unwinding of the cable 25.

In preparation for picking up of the glider 28, the cable 25 is completely unwound from the drum 16 as shown in Figs. 1 and 2, pulled taut, and its eye 26 engaged with the hook 27 on said glider. Through incidental rotation of the drum 17 by reason of its chain connections 36 with the drum 16, the cable 33 is concurrently wound onto the drum 17, after having been previously doubled upon itself and lightly tied by the tape B, and its free end tucked beneath that end which, as before stated, is fixedly clamped to the latter drum. With this accomplished, the loop 34 of the cable 33 is spread horizontally and engaged over the tops of the standard 31. Thereupon the loop 30 of the tow line 29 is similarly engaged over the tops of the standards 31 with the excess length thereof to one side, and lightly

taped to the loop 34 of cable 33 at a few spaced points as indicated at C in Fig. 3. The towing craft, herein exemplified as a powered plane 46, is provided at the region of its gravity center with a pendent pick-up projection in the form of a hook 47 which is preferably arranged so that it may be retracted when not used for towing.

All being now in readiness, the airplane 46 is flown from rearward of the glider 28 and piloted so that its hook 47 will, in passing, engage the loops 30 and 34 of the tow lines 29 and the cable 33 supported horizontally open at the tops of the standards 31 as shown in Figs. 1 and 3, the engagement of both said loops being insured by virtue of their being lightly taped together at the points C. Immediately upon this engagement, the pull on the cable 33 causes the drum 17 to rotate, which, by virtue of the sprocket chain connections 36, in turn causes rotation of the drum 16 and in turn winding of the cable 25 to draw the glider 28. The drums 16 and 17 are so proportioned and shaped as to determine uniform acceleration of the glider until it attains the speed of the plane 46, the cables 25 and 33 pulling oppositely as they move linearly with said drums rotatively at synchronous speeds. During the pick-up interval, the amount of the cable 33 drawn off at one revolution of the drums is equal to $\pi \times D$ (the diameter of the drum 17) and the amount of the cable 25 taken up is equal to $\pi \times d$ (the diameter of the drum 16). Thus as D and d gradually approach each other, the speed of the glider increases until the cables reach the end portions of equal diameter of the drums 16 and 17, when the glider will have attained the speed of the plane. At the stage last described, the slack of the tow line will be substantially absorbed and the eye 26 at the free end of the cable 25 will drop off the hook 27 on the glider 28 as the latter passes over the reeling unit 15, as shown in Fig. 4, the cable 33, by reason of having its loose end freed from the drum 17, reaving at the same time through the hook 47 on the airplane 46, as also shown in Fig. 4, with attendant rupture of the tape bands B and C. The length of the tow line 29 is critical, it being made equal approximately to the doubled length of the cable 33. For all practical purposes, the speed of the plane 46 is kept constant during the pick up. The tendency of the plane to slow down at the time of initial engagement of its hook with the loops of the tow line 29 and the cable 33 should be compensated by the opening of the throttle of the plane motor by the pilot. The pick up is thus effected substantially without impartation of abrupt strains either to the glider or the plane. In practice a suitable brake means is provided to prevent excessive over-running of the drums 16 and 17. Such brake means may be of any approved type and for this reason illustration thereof has been omitted from the drawings. For the purposes of re-winding, I may provide a crank handle for application to either of the drum shafts.

Having thus described my invention, I claim:

1. Glider pick-up apparatus including a standard adapted to releasably support at an elevation the free end of a tow line extending forwardly from a glider positioned at rest on the ground; an auxiliary cable adapted to be connected at one end to the front of the glider; a second cable adapted to have one of its ends releasably supported by the standard so that it and the free end of the tow line can be picked up by a catch projection on a passing towing

craft in flight; a reeling unit rearward of the standard operated through pull on the second cable by the towing craft including means to gradually take up the first cable and impart accelerated movement to the glider until it attains the speed of the towing craft, and means automatically operative to effect release of the cables respectively when the speed of the glider is substantially equal to that of the towing craft for draft thereafter by said tow line.

2. Glider pick-up apparatus according to claim 1, in which the reeling unit comprises tapered drum means whereto the first mentioned cable is connected to the small end of said means so as to wind toward the large end of the latter during the pick up, and in which the second cable is wound upon the drum means so as to unwind toward the small end of the latter during the pick up.

3. Glider pick-up apparatus according to claim 1, in which the reeling unit comprises a pair of intergeared tapered drums; in which the first mentioned cable is connected to the periphery of one of said drums at the small end so as to wind toward the large end of said drum during the pick up; and in which the second cable is wound upon the other drum so as to unwind from the large end of the latter toward the small end during the pick up.

4. Glider pick-up apparatus according to claim 1, in which the reeling unit comprises a pair of intergeared tapered drums; in which the first mentioned cable is connected to the periphery of one of said drums at the small end so as to wind toward the large end of said drum during the pick up; and in which the second cable is wound upon the other drum so as to unwind from the large end of the latter toward the small end during the pick up; and in which the diameter of the small end of the last mentioned drum is equal to the diameter of the large end of the first mentioned drum.

5. Glider pick up apparatus according to claim 1, in which the reeling unit comprises a pair of intergeared tapered drums; in which the first mentioned cable is connected to the periphery of one of said drums at the small end so as to wind toward the large end of said drum during the pick up; in which the second cable is wound upon the other drum so as to unwind from the large end of the latter toward the small end during the pick up; in which the taper of the last mentioned drum is straight; in which the taper of the first drum is curved; and in which the diameter of the small end of said other drum is equal to the diameter of the large end of the first drum.

6. Glider pick-up apparatus according to claim 1, further including a bearing frame in which the reeling unit includes drums which are journaled in juxtaposed relation; and means by which

said drums are intergeared comprising sprockets on their respective axes, and a chain connecting said sprockets.

7. Glider pick-up apparatus according to claim 5, further including a supporting frame having side standards with bearings in which the reeling unit includes drums which are journaled in juxtaposed relation, a traversing guide for the first cable; a crosswise screw spindle engaging the 10 traversing guide and also journaled in the side standards of the bearing frame and driven from one of the drum axes, the thread of said spindle terminating short of said standards to permit the guide to run off after completion of its travel in either direction; and compression springs at the insides of said standards to cause the guide to automatically re-engage the thread upon subsequent reversal of said spindle.

8. Glider pick-up apparatus according to claim 20 1, in which the reeling unit comprises tapered drum means whereto the first cable is fixedly connected to the periphery at the small end; and whereto one end of the second cable is fixedly connected to the periphery of said drum means 25 at the large end; in which said second cable is wound double in readiness for the pick-up operation upon the drum means with its other end tucked beneath the fixed end so that a loop is formed for engagement by the catch projection 30 on the towing craft, capable of freeing itself from said projection after complete unreeling of said second cable.

9. Pick-up apparatus of the character described including a pair of cables; and a reeling 35 unit comprising an accelerating drum with a varying taper to the small end of which one of the cables is connected so as to wind toward the larger end of the drum; a driving drum with a uniform taper to the larger end of which the other 40 cable is connected so as to unwind toward the smaller end during the pick-up; and gearing connecting the drums for rotation together.

10. Pick-up apparatus according to claim 9, in which the diameter of the small end of the 45 driving drum is equal in diameter to the large end of the accelerating drum so that the linear speeds of the two cables will be the same at the end of the pick-up operation.
